(57) **CLAIM**

We claim the ornamental design for extendable battery charger, as shown and described.

DESCRIPTION

FIG. 1 is a perspective view showing the top, front, and right side of the extendable battery charger of the present invention in its retracted position;

FIG. 2 is a top view of the extendable battery charger of the present invention in its retracted position;

FIG. 3 is a view of the first side of the extendable battery charger of the present invention in its retracted position;

FIG. 4 is a bottom view of the extendable battery charger of the present invention in its retracted position;

FIG. 5 is a front view of the extendable battery charger of the present invention in its retracted position;

FIG. 6 is a rear view of the extendable battery charger of the present invention in its retracted position;

FIG. 7 is a perspective view showing the top, front, and right side of the extendable battery charger of the present invention in its extended position;

FIG. 8 is a top view of the extendable battery charger of the present invention in its extended position;

FIG. 9 is a view of the first side of the extendable battery charger of the present invention in its extended position;

FIG. 10 is a bottom view of the extendable battery charger of the present invention in its extended position;

FIG. 11 is a front view of the extendable battery charger of the present invention in its extended position; and,

FIG. 12 is a rear view of the extendable battery charger of the present invention in its extended position.

The first side elevational view shown in FIG. 3 is a mirror image of the opposite side of the extendable battery charger of the present invention.
